UNITED STATES PATENT OFFICE.

JOSIAH FAIRNEY, OF WAYNESBOROUGH, PENNSYLVANIA.

DESIGN FOR A STRAW-RACK FOR GRAIN-SEPARATORS.

SPECIFICATION forming part of Design No. 30,581, dated April 18, 1899.

Application filed March 14, 1899. Serial No. 709,091. Term of patent 14 years.

To all whom it may concern:

Be it known that I, JOSIAH FAIRNEY, a citizen of the United States, residing at Waynesborough, in the county of Franklin and State 5 of Pennsylvania, have invented and produced a new and original Design for a Straw-Rack for Grain-Separators; and I do hereby declare the following to be a full, clear, and exact description of the invention, such as will enable 10 others skilled in the art to which it appertains to make and use the same.

In the drawings, Figure 1 is a side view of the straw-rack. Fig. 2 is a plan view of the straw-rack.

15 As shown in the drawings, the leading or material feature of the design consists in a straw-rack provided with a series of bars waved or corrugated upon curved lines in the direction of their length and having narrow spaces or openings between them.

20 A are the bars, which are waved or corrugated upon curved lines in the direction of

their length. The waves or corrugations consist of convex upper parts *b* and concave lower parts *c*, arranged alternately in the 25 same vertical plane, and the convex parts *b* are of greater radius than the concave parts *c*.

D are cross-pieces which hold the bars *A* in position, so that narrow parallel spaces or openings *d* are maintained between the bars. 30

E is a concavo-convex projection extending lengthwise along the upper surface of each bar *A* and stiffening it.

What I claim is—

The design for a straw-rack for a grain-separator, substantially as herein shown and described. 35

In testimony whereof I affix my signature in presence of two witnesses.

JOSIAH FAIRNEY.

Witnesses:

FRANK O. SHIESS,
E. B. FAIRNEY.
